UNITED STATES PATENT OFFICE.

STEPHEN L. BROWN, OF FRANKLIN, PENNSYLVANIA.

AIRLINE PUMP.

Application filed November 3, 1927. Serial No. 230,782.

The present invention relates to an air-line pump and is designed for the purpose of feeding air to an airline for driving various mechanisms such as pneumatic hammers and the like.

An object of the invention resides in the provision of a structure wherein the air is compressed and driven through a cooler and then further compressed and forced into an air line, the structure being of such a nature that the temperature of the air is maintained relatively low.

A further important object of the invention resides in the provision of a structure of this nature which is thoroughly efficient and reliable in operation and well adapted to the purpose for which it is designed.

With the above and numerous other objects in view as will appear as the description proceeds, the invention resides in certain novel features of construction, and in the combination and arrangement of parts as will be hereinafter more fully described and claimed.

25 In the drawing:

Figure 1 is a longitudinal vertical section through the structure embodying the features of my invention,

Figure 2 is a transverse vertical section taken substantially on the line 2—2 of Figure 1,

Figure 3 is a longitudinal section through the piston taken at right angles to that shown in Figure 1,

Figure 4 is a longitudinal section through the pistons as disposed in Figure 1.

Figure 5 is a longitudinal section through the outer piston structure,

Figure 6 is a longitudinal section through the inner piston structure,

Figure 7 is a sectional view through one of the cylinder heads,

Figure 8 is a longitudinal section through the other cylinder head, and

Figure 9 is an end elevation of the inner piston.

Referring to the drawing in detail it will be seen that the numeral 5 denotes a cylinder, the wall of which is hollow and formed with an annular central passage 6 from which leads into the cylinder ports 7. An entrance 8 is provided in the cylinder to the passage 6. On one side of the cylinder 5 there is formed a longitudinal passage 9 with a central outlet 10 and end intakes 11. Plates 12 are positioned at the ends of the

cylinder 5 and are formed with openings 13 concentric in respect to the bore of the cylinder and of less diameter than the bore. Openings 14 are formed in the plates in registry with openings 11. Cylinder heads 15 and 15' are positioned, one adjacent each plate 12, and are formed with inner annular passages 16 from which lead openings 17 in registry with openings 14 and to which lead annular slots 18 from the bore of the cylinder. These cylinder ends are further provided with annular passages 19 having openings 20 and openings 21.

A head 22 is formed with the hollow plate *a* having openings 23 and 24. The openings 23 register with the openings 21 of one cylinder end 15. The opening 24 is centrally located in the inner wall of the plate *a* and a hollow cylindrical member 25 projects from the outer wall through the opening 24 and has a longitudinal channel 26 partly covered by a wall *c*. Pipes 27 and 28 lead from openings 20 to a cooler 29 of any preferred construction. A head 30 is positioned against the cylinder end 15 and

comprises a hollow plate *a'* having openings 31 registering with openings 21 of the cylinder end 15', having openings 32 communicating with the bore of the cylinder end 15' 85

and formed with a cylindrical member *b'* provided with slideways 34 and opening 33 for water.

A piston structure *P* is slidable in the cylinder 5 and its ends 15 and 15'. A piston *P'* is slidable in the piston structure *P*. The piston structure *P* includes a cylinder 35 formed by a hollow wall with partitions to provide passages 36 having longitudinally spaced intake ports 37 and 38 one to each side of the center of the cylinder 35 (said intake ports being circumferentially spaced) and opening into the cylinder 35; said hollow wall having an outlet port 39 opening into the cylinder 35. The hollow wall of the cylinder 35 is further provided with passages 40 and 41 terminating in outlets 42 and 43 respectively for registry with slots 18 of the cylinder ends 15' and 15 respectively, said passages 40 and 41 also terminating in intakes 44 and 45 opening interiorly of the cylinder 35. Piston heads 46 are formed on the cylinder 35 one to each side of the center thereof. These piston heads 46 are slidable in the bore of the cylinder 5 between the plates 12, while the cylinder 35 is slidable in the bores of the cyl-

105

110

115

inder ends 15 and 15'. The members *b* and *b'* extend into the ends of the cylinder 36 having piston fits therewith. Portions of the walls of the cylinder 36 are solid and provided with orifices 47 and 48.

The piston *P'* is hollow and has ports 49 one to each side of its center. Exterior circumferential channels 50 are formed on the piston *P'*, the ports 49 being between the channels. Passages 51 are formed in the wall of the piston *P'* leading from points just outside of the channels 50 to the opposite end of the piston *P'*.

Any suitable means is provided for reciprocating the pistons *P* and *P'* one a little in advance of the other. In the present instance this motion is accomplished by means of rods 53 extending from cross heads 54 and engaged through one end with the cylinder 36 of the piston *P*. A rod 55 extends through opening 34 and is engaged with the piston *P'* at one end and at its opposite end with a cross head 56. The cross heads are mounted in suitable slideways and operable by means of connecting rods 58 engaged with cranks 59 slightly offset in respect to each other. These cranks 59 are on a shaft 60. Thus by the turning of the shaft 60 the cranks through the mechanism just described reciprocate the pistons *P* and *P'* back and forth one a little in advance of the other because of the offset relation of the cranks 59.

It is thought that the details of construction have been sufficiently described to enable one skilled in the art to follow the air through the apparatus when in operation. Starting with the parts in the position shown in Figure 1 and presuming that the shaft 60 is rotating in a clockwise direction it will be seen that the space between piston heads 46 within the cylinder 5 is open to the atmosphere through the entrance 8, and openings 7. This air is also free to flow through orifice 47 and a port 49 registering therewith through the piston *P'* and out through the other port 49 which is in registry with passage 48 leading into that portion of the cylinder 5 between the right hand piston head 46 and the right hand plate 12. The piston *P'* will move a slight distance to the left as the piston *P* starts to the right which will cause the registration of the orifice 47 with the right hand opening 49 and the registration of the orifice 48 with the right hand channel 50 so that as the pistons move to the right the air will be forced from the right hand end of the cylinder 5 through

the right hand orifice 48 around the channel 50 through the port 37, through the passage 60 36, opening 39, through the hollow plate *a* of the head 22 through the opening 23 through the compartment 19 of the cylinder end 15, through the pipe 27 through the cooler 29, through the pipe 28 into the compartment 19 of the head 30 into the plate *a'* into the passage 40, port 37 registering with passage 51 to the right causing the air to flow into the right hand end of the cylinder 36 to be compressed between the piston *P'* and the inner end of the member *b'* of the head 30 and to be forced out through opening 42 into the right hand cylinder end compartment 16 and out through passage 11 into the line 10. This action is continuous as the cylinders reciprocate back and forth and it is thought that the air on the left hand side of the apparatus may be followed without a detailed description. It is thought that the construction, operation, utility and advantages of this invention will now be clearly understood by those skilled in this art without a more detailed description thereof. The present embodiment of the invention has been disclosed in detail merely by way of example since in actual practice it attains the feature of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

An apparatus of the class described comprising a cylinder formed with an intake passage and an outlet passage, a piston slideable in the cylinder and having a cylinder portion with a pair of heads one spaced to each side of the center of the cylinder portion, the space between the heads being in communication with the intake passage, a second piston slideable in the cylinder portion, said cylinder portion having a plurality of longitudinal passages for leading the air from the cylinder by the movement of the heads therein to a by-pass and passages to receive the air from the by-pass to lead the air into the cylinder portion to be acted upon by the second piston and forced into the outlet passage.

In testimony whereof I affix my signature.
STEPHEN L. BROWN.
